ATTACHING MEANS FOR COIL SPRINGS AND THE LIKE

Samuel S. Bernstein, Beverly Hills, Calif.

Application December 1, 1937, Serial No. 177,551

6 Claims. (CL. 85—49)

This invention relates generally to an attaching or fastening means such as wire staples or the like. More particularly the invention relates to means for attaching coil springs such as are used in upholstering construction to the spring supporting fabric or webbing.

Although the fastening means of this invention is particularly designed for fastening upholstering coil springs to the spring supporting fabric or webbing, it is contemplated that the fastening means disclosed herein is suitable for other purposes such as the fastening of other objects to cloth, paper or the like, and to fastening two or more thicknesses of cloth, paper or the like to each other. For the purpose of this disclosure however, the fastening means is shown and described with particular reference to the fastening of coil springs to a spring supporting fabric or webbing.

20 In the ordinary upholstery construction it is the usual practice to fasten the coil springs to the spring supporting fabric by means of a continuous length of twine which is threaded around the lower coil of the spring at various points and through the fabric. The disadvantages of this construction are that it is a slow means of installing the springs; when the springs are installed they are often insecurely held, depending upon the skill of the workman; after the upholstery has been used the springs tend to work loose, thereby causing wear of the fabric and the twine; and finally if one stitch of the twine breaks it permits all of the springs which the single continuous twine holds to slip from the proper position on the fabric.

In view of the disadvantages of the ordinary means of attaching springs to the supporting fabric, it is a primary object of this invention to provide an improved attaching means for securing coil springs to the spring supporting fabric which may be quickly installed and when so installed will securely and firmly hold the spring and which will not wear out or permit the spring to slip and wear the fabric, said means being in the form of individual units so that if one breaks, the others will hold each spring securely.

To accomplish the above mentioned object it is a further object of this invention to provide what may be termed a metal staple. Ordinary staples, such as used for attaching papers and the like together are unsuitable for the purpose of attaching coil springs to fabric, chiefly because they require a stapler which has a base or anvil portion which must necessarily be on the opposite side of the article being stapled and

against which the staple must be hammered, driven or forced in order to bend it over behind the article being stapled.

Therefore it is a further object of this invention to provide a staple which requires no base or support or anvil against which it must be forced to bend it to the proper holding or closed position and which may be easily installed by pliers or suitable apparatus having contractible jaws or by mechanism capable of bending the staple so that it is bent back upon itself. It is also an object of this invention to provide a staple of the type indicated which tends to bite into the fabric and which needs little or no pressure against it to force it into the fabric.

It is also an object of this invention to provide a staple of the type indicated which tends to bite into the fabric from the reverse side after it is squeezed into the closed or holding position and which, when so closed, does not leave points or other sharp projections on the rear or under side of the fabric.

These and other objects will be apparent from the drawing and the following description. Referring to the drawing, which is for illustrative purposes only,

Fig. 1 is a perspective view showing a coil spring secured to the upper surface of a spring supporting fabric in the manner contemplated by this invention.

Fig. 2 is an inverted perspective view of the preferred form of staple or fastener of this invention.

Fig. 3 is an end elevation of a staple in holding or closed position shown with relation to a fragment of a coil spring and a section of spring supporting material.

Fig. 4 is an inverted perspective view of a modified form of staple.

Fig. 5 is an end elevation of the staple shown in Fig. 4 in the closed or holding position, showing it in relation to a lower coil of a spring and supporting fabric.

Fig. 6 is a perspective view of another form of staple.

Fig. 7 is an end elevation of the staple of Fig. 6 and a fragmentary view of a modified form of jaw mechanism for use in connection with the staple shown in Fig. 6.

Referring to Fig. 1 there is shown a spring supporting fabric 50 upon which is supported a coil spring 51 of the type commonly used in upholstery construction. The lower coil 52 of the spring is stapled to the fabric by the staples indicated by reference numeral 53. This illus-

trates the manner in which the coil spring is stapled to the supporting fabric by means of the staple or fastening means of this invention. For the purpose of illustration the fabric 50 has been shown but it is contemplated that the stapling means may be used in connection with interlaced webbing or other types of spring supports.

In Figs. 2 and 3 there is shown a preferred form of staple or fastener. In Fig. 2 the staple 10 is shown inverted for clarity of illustration. The staple comprises a top portion 54 apertured at 55, the portion being slightly concavely bent at 56 to insure the staple bending properly when compressed. The staple is bent back upon itself 15 by the folds 57, forming the under portions 58. These portions 58 each terminate in a pair of curved prongs, generally indicated by reference numeral 60. These prongs are curved downwardly and slightly outwardly so that when the 20 central portion 54 of the staple is squeezed they continue to follow the curve initially described by them and further penetrate the fabric into which the points of the prongs may be forced by slight pressure, entering the fabric on one side and 25 reentering it again from the reverse side as the prongs rotate about an axis at the center of the staple, leaving no points or sharp edges underneath the fabric. It will be noted that when the staple is squeezed to the closed position the aperture or hole 55 in the top portion 54 becomes a 30 notch fitting over the wire (lower coil of a spring) to be stapled. This is shown in Fig. 1 and is apparent from Fig. 3 where the staple is shown closed and securing a section of spring to a 35 supporting fabric.

In Fig. 4 is shown in inverted position what will be termed a single type staple or fastener, as contrasted with what may be termed a double type staple of the previous figure. This staple 40 comprises a body portion 62 which is apertured at 63 and slightly inwardly curved at 64. Extending downwardly from the plate portion are the prongs 65 which are outwardly curved at their ends. The staple is adapted to be squeezed closed 45 to the position shown in Fig. 5 by the same staple mechanism as is used in connection with the staple of Fig. 2, the aperture 63 becoming a notch for holding the coil spring section 52.

In Fig. 6 there is shown a modified form of 50 staple which comprises a slightly corrugated top portion 66 having a transverse convex portion from which extend at each end pairs of inwardly curved prongs 67. This staple is adapted to be closed over the coil spring (see Fig. 7) by means 55 of any suitable jaw mechanism which has added thereto the centrally depending abutment member 68 which acts as a stop means on the top of the staple to prevent it from expanding upwardly

when the jaws are contracted. The abutment member is mounted on the pivot pin of the jaw mechanism by means of an aperture 69. For guiding the member 68 centrally of the jaws, extended portions 69 are provided which slide in slots 69' of the jaw mechanism.

I claim as my invention:

1. A staple comprising a centrally apertured metal strip terminating in pronged end portions, said metal strip being bent back upon itself adjacent each end to form a substantially flat apertured top portion and two under portions, the pronged end portions being curved downwardly and outwardly.

2. A staple comprising a centrally apertured metal strip terminating in pronged end portions, said metal strip being bent back upon itself adjacent each end to form an apertured top portion and two under portions, the pronged end portions being curved downwardly and outwardly, said top portion being slightly concavely bent transversely thereof.

3. A metal staple comprising a centrally apertured top portion having a slight concave transverse bend, and downwardly and outwardly extending prong portions, said prong portions being spaced from said transverse bend, said staple being adapted to be squeezed to form a fold in said top portion to cause said aperture to form a notch and to cause said prong portions to move outwardly and upwardly.

4. A metal staple comprising a top portion having a slight concave transverse bend, and having downwardly and outwardly extending prong portions, said prong portions being spaced on opposite sides of said bend, said staple being adapted to be squeezed on opposite sides of said bend whereby said bend is increased to a fold and said prong portions are moved outwardly and then upwardly.

5. A staple comprising a centrally apertured metal strip having a body portion and a pair of prong portions on opposite sides of said body portion, each pair of said prong portions extending below said body portion at substantially right angles thereto, the ends of the prong portions of each of said pairs being divergently disposed with relation to each other, said strip having a slight concave bend extending across the middle of said body portion, said bend being between the individual prong portions of each of said pairs of prong portions.

6. A staple comprising a top portion having opposed prongs extending downwardly and outwardly, said prongs being adapted to move outwardly and upwardly when said top portion is bent upon itself.

SAMUEL S. BERNSTEIN.
